HYDROCARBON CONVERSION

Harrison C. Mayland, Chicago, Ill., assignor to
Universal Oil Products Company, Chicago, Ill.,
a corporation of Delaware

Application September 19, 1941, Serial No. 411,448

3 Claims. (Cl. 196—52)

This invention relates to a process for the catalytic cracking of a hydrocarbon oil for the production of high octane number gasoline wherein the activity of the catalyst gradually decreases during the processing cycle due to the deposition of deleterious carbonaceous materials on the catalyst surfaces and wherein the activity of the catalyst is restored by the periodic regeneration of the catalyst by the combustion of the carbonaceous materials with hot oxygen containing gases. More specifically, this invention is concerned with catalytic cracking process of the type described above which also includes the recycling of the insufficiently converted hydrocarbons back to the catalytic mass.

One of the main difficulties encountered in most of the present catalytic operations lies in the fact that the reflux condensate formed in the operation is refractory and is not readily susceptible to further catalytic treatment. If this reflux condensate is admixed with the fresh feed and recycled back to the catalyst zone, the conversion per pass through the catalyst zone greatly decreases. This decrease in conversion per pass makes it necessary to operate using high recycle ratios which not only decreases the plant capacity considerably but also increases the repumping and reheating requirements to produce the desired quantity of gasoline.

Increasing the severity of the processing while aiding in decreasing the recycle ratio has additional disadvantages in that greater amounts of light gases and catalyst deposit are formed. This additional catalyst deposit increases the capacity of the regenerating equipment necessary, thereby considerably increasing the cost of the operation.

To avoid the difficulties recited above, it has been proposed to conduct the catalytic operation on a once-through basis wherein only the fresh feed is charged to the catalyst and the refractory reflux condensate is cracked in a thermal operation. This method of conducting the operation would, of course, have the advantage of eliminating the difficulties attending the recycling of a highly refractory reflux condensate back to the catalyst mass but it too has definite disadvantages.

It is known that in the catalytic cracking operation, a gasoline is produced which has a high antiknock value, usually between 8 and 12 octane numbers higher than the antiknock value of gasolines produced thermally. Therefore, when charging a given amount of oil, it is more desirable to crack the greater proportion of the oil catalytically to obtain a greater proportion of a

higher octane number fuel for the same quantity of charging oil.

The process disclosed herein combines the advantages of a total recycle operation with those of the once-through operation while substantially eliminating the difficulties inherent in both processes.

It has been discovered that as the catalyst activity decreases during the processing cycle due to deposition of carbonaceous materials on the catalyst surface which, of course, results in a decrease in the conversion per pass, there is a corresponding decrease in the refractoriness of the reflux condensate formed. This refractoriness decreases 10 fairly rapidly during the processing cycle and it was found that the reflux condensate produced during the major part of the processing cycle was susceptible to further catalytic treatment. The present invention discloses a process wherein the 15 reflux condensate produced during a particular portion of the process period which has attained a definite degree of susceptibility to further catalytic cracking is recycled back to the catalyst. Evidences have been found which seem to indicate that there is a relationship existing between the paraffinic nature of the reflux condensate and its 20 susceptibility to catalytic cracking. Experimental tests have shown that the more paraffinic the reflux condensate is the greater its susceptibility 25 to catalytic cracking. The relative paraffinic nature of a particular reflux condensate is obtained by the determination of its characterization factor which will provide a simple method for maintaining and controlling the operation at an optimum 30 recycle ratio. This characterization factor is an indication of the relative paraffinic nature of a hydrocarbon oil. When dealing with a pure hydrocarbon this factor is defined as a cube root of its absolute boiling point in degrees Rankine divided by the specific gravity at 60° F. However, when dealing with complex mixtures such as a hydrocarbon oil the characterization factor of the oil may be defined as the cube root of its cubic 35 average boiling point in degrees Rankine divided by the specific gravity at 60° F. When a complete chemical analysis is available the cubic average boiling point may be calculated as a cube of a sum of the product of the volume fraction times the cube root of the boiling point of each 40 component expressed in degrees Rankine. If a complete analysis is not available the cubic average boiling point can be estimated by the volumetric boiling point by subtracting a correction obtained by a correlation of the volume average boiling point and the Engler distillation 45 50 55

curve slope. When this ratio is of the order of 12 or more, the stock is predominantly paraffinic, and as the characterization factor decreases the paraffinicity of the hydrocarbon oil also decreases.

As has been previously stated, the feature of this invention lies in the recycling of that portion of the reflux condensate which has attained a definite degree of susceptibility to further catalytic cracking as determined by its characterization factor. By recycling this portion of the reflux condensate having the desired degree of paraffinicity, the optimum quantity of the charging stock can be catalytically cracked without introducing the difficulties attending the use of a high recycle ratio in a total recycle operation.

The optimum portion of the reflux condensate will, of course, vary with the charging stock and catalyst used, but it has been found that it is usually possible to maintain the most efficient catalytic cracking operation if the characterization factor of the reflux condensate recycled back to the catalytic conversion zone is of the order of about 11 or higher.

It must be understood that this characterization factor referred to above does not mean the average factor but refers to the instantaneous value of this factor. For instance, during the operation, the value of the characterization factor of the reflux condensate formed gradually increases. When this factor reaches about 11 this material is recycled back to the catalyst zone. The material formed in the early part of the cycle having a lower characterization factor is either sent to storage or charged to some other process such as a thermal cracking process.

In one specific embodiment the present invention discloses a catalytic cracking process which comprises contacting a hydrocarbon oil under cracking conditions of temperature and pressure with a cracking catalyst disposed in a reaction zone, withdrawing the reaction products, fractionating said products and separating the gasoline boiling range materials from the insufficiently converted hydrocarbons, and recycling back to the catalyst, that part of the insufficiently converted hydrocarbons which has attained a desired degree of paraffinicity.

The invention will be more fully understood by the description of the accompanying drawing which illustrates in conventional side elevation one form of apparatus in which the objects of the invention can be accomplished.

Referring to the drawing, the charging stock which may comprise, for example, a Mid-Continent gas oil, is introduced through line 1 containing valve 2 into pump 3 which discharges through valve 4 and is thereafter commingled with insufficiently converted hydrocarbons formed as hereinafter set forth. The resulting mixture passes through line 5 into heating coil 6 disposed in furnace 7. The resulting mixture is heated to the desired temperature and leaves heating coil 6 disposed in furnace 7 and is conducted through line 8 containing valve 9 into reactor 10 wherein it is contacted with a catalytic mass at suitable conditions for the production of lower boiling range hydrocarbons. The temperature in reactor 10 may range from 700-1200° F. and preferably from 800-1000° F., and the pressure may range from substantially atmospheric to 200 pounds or more per square inch.

Reactor 10 may comprise, for example, a conversion zone of the heat exchanger type wherein the catalyst is contained in a plurality of elongated tubular elements of relatively small diameter, provisions being made for passing some suitable heat convective fluid such as combustion gases in indirect heat exchange relationship with said tubular elements to supply heat to the reactants during conversion and to cool the catalyst and regenerating gases during regeneration. Reactor 10, on the other hand, may comprise a cylindrical vessel containing one or a plurality of beds of catalytic material, said vessel being insulated to reduce the radiation losses therefrom, so that conversion reaction may be accomplished substantially adiabatically.

The catalyst disposed in reactor 10 may comprise, for example, powder, pellets, or granules containing synthetically prepared, purified silica, or other siliceous and refractory materials composed with one or more of the compounds selected from the group consisting of alumina, zirconia, and thoria. In addition, the hydrosilicates of alumina, acid treated clays, or the like, have also been found to be effective in the cracking treatment of hydrocarbon vapors. Although the catalysts above recited are generally considered to be the preferred catalysts, their use is not to be construed as a limiting feature, for various other catalysts well-known to those in the art may be employed within the broad scope of the invention.

During the catalytic cracking of hydrocarbon oils, considerable amounts of carbonaceous materials deposit on the catalyst surfaces thereby decreasing the activity of the catalyst. It is necessary, therefore, to periodically regenerate the catalyst by the combustion of the carbonaceous materials with hot oxygen containing gases. It is desirable, therefore, in order that the operation may be carried out as a continuous process to employ at least two reactors so that while the catalytic material in one reactor is being used for processing the hydrocarbon reactants, the catalytic material in the other reactor may be undergoing regeneration. The invention disclosed herein is particularly adaptable to a system using more than two reactors in which the processing period is staggered, as will be more fully explained later in this specification.

The reaction products leaving chamber 10 are conducted through line 11 containing valve 12 into fractionator 13 which is operated at substantially the same or at a reduced pressure in reference to reactor 10. In fractionator 13, the gasoline boiling range hydrocarbons are separated from the higher boiling hydrocarbons and the former materials are withdrawn through line 14 containing valve 15 and may be thereafter cooled, condensed, and separated from the light gases by any of the well known methods of stabilization.

The higher boiling materials are withdrawn through line 16' and may be conducted into either line 17 or 18 depending upon the character of the materials. During the first part of the processing period in reactor 10, the insufficiently converted hydrocarbons separated out in fractionator 13, will possess a low degree of paraffinicity and will not be very susceptible to further catalytic cracking. Therefore, during this part of the processing cycle, the insufficiently converted hydrocarbons will be withdrawn through line 16' into line 17 containing valve 18 and sent to storage. These materials may be cracked, if so desired, in a non-catalytic operation, thereby augmenting the total yield of gasoline obtained from a given quantity of the charging stock.

As the processing cycle continues, the catalyst

activity decreases due to deposition of carbonaceous material on its surface. The paraffinicity of the reflux condensate formed gradually increases until a reflux condensate having the desired characterization factor is formed. It is apparent that the desired characterization factor will vary depending upon the catalyst and the charging stock being used but ordinarily the desired reflux condensate will have a characterization factor of the order of about 11 or higher. Therefore, when the characterization factor of the higher boiling materials separated out in fractionator 13 reaches the desired predetermined value, valve 18 is closed and the hydrocarbons are conducted through line 19 containing valve 20 into reservoir 21. The recycle oil is withdrawn from the reservoir through line 22 containing valve 23 in pump 24 which discharges through valve 25 into line 26. The hydrocarbons conducted through line 26 are mixed with the fresh feed entering through valve 4 and the mixture is sent to heating coil 5. The recycle ratio is proportioned so that a constant rate of recycle oil and fresh feed may be maintained, thereby permitting the constant firing of furnace 7 without the introduction of any additional heating problems.

The invention disclosed herein is also adaptable to many other methods of operation. For example, a multiple reactor system may be used in which the processing cycle is staggered, perhaps with a lag of one-quarter cycles between reactors. By the introduction of a second fractionating step, it would be possible to recycle the higher boiling hydrocarbons from the reaction zone which is farther advanced in the processing cycle to the reaction zone just starting the processing cycle, thereby conducting the same type of cracking operation as described previously in this specification.

The following examples will present the distinct advantages obtained when using the process disclosed herein. The preceding description of the drawing and the following examples are not intended to place any undue limitations on the present invention since there are many modifications which will fall under its broad scope.

Example

A 31.5° A. P. I. gravity Mid-Continent gas oil is contacted at a temperature of 950° F. under a pressure of 30 pounds per square inch gauge and at a liquid hourly charge rate corresponding to a space velocity of 1 with a composite catalyst comprising silica, alumina, and zirconia for a two hour processing period. During the operation a portion of the reflux condensate formed is being continually withdrawn and sent to storage. The remaining portion of reflux condensate is sent back to the reaction zone. The average characterization factor of the withdrawn reflux condensate is about 11.5. The yields are 39.0% gasoline, 9.1% gas, 2.5% catalyst coke, and 49.5% fractionator bottoms.

The same oil is charged to the catalyst under the same processing conditions but with the re-circulation of only that portion of the insuf-

ficiently converted hydrocarbons having a characterization factor of 11 or higher. The more refractory materials having a characterization factor below 11 which are formed during the early portion of the processing cycle are withdrawn to storage. When the characterization factor of the reflux condensate withdrawn from the fractionator reaches about 11, this material is recycled back to the reaction zone. The resulting yields are 7% gas, 41.7% gasoline, 1.8% catalyst coke, and 49.5% fractionator bottoms. The withdrawn fractionator bottoms have an average characterization factor of 10.7.

The utility of the present invention is shown by the preceding examples. When using the process disclosed herein, the gasoline yield is increased approximately 7%, the gas yield decreased approximately 22%, and the catalyst coke is decreased approximately 28%.

I claim as my invention:

1. A process for the conversion of hydrocarbon oil which comprises subjecting said hydrocarbon oil to contact under suitable processing conditions with a cracking catalyst disposed within a reaction zone, separating the gasoline boiling range materials from the insufficiently converted hydrocarbons, withdrawing insufficiently converted hydrocarbons formed during the early portion of the processing period having a characterization factor below about 11, and recycling the insufficiently converted hydrocarbons formed during the second portion of the processing period having a characterization factor in excess of about 11 back to the reaction zone.

2. A process for the conversion of hydrocarbon oil which comprises subjecting said hydrocarbon oil to contact at a temperature within the range of about 700 to 1200° F. with a cracking catalyst disposed within a reaction zone, separating gasoline boiling range materials from insufficiently converted hydrocarbons, withdrawing insufficiently converted hydrocarbons formed during the early portion of the processing period having a characterization factor below about 11, and recycling insufficiently converted hydrocarbons formed during the second portion of the processing period having a characterization factor of at least 11 back to the reaction zone.

3. A process for the conversion of a hydrocarbon oil which comprises subjecting said hydrocarbon oil to contact at a temperature within the range of about 700 to 1200° F. and under a pressure of atmospheric to about 200 pounds per square inch superatmospheric with a cracking catalyst disposed within a reaction zone, separating gasoline boiling range materials from insufficiently converted hydrocarbons, withdrawing insufficiently converted hydrocarbons formed during the early portion of the processing period having a characterization factor below about 11, and recycling insufficiently converted hydrocarbons formed during the second portion of the processing period having a characterization factor of at least 11 back to the reaction zone.

HARRISON C. MAYLAND.
